US0D1052702S

(12) **United States Design Patent** (10) **Patent No.:** **US D1,052,702 S**
(45) **Date of Patent:** **** Nov. 26, 2024**

(54) **SINK DRAINAGE PLUG**

(71) Applicant: **XIAMEN AOMUTE TECHNOLOGY CO., LTD**, Xiamen (CN)

(72) Inventor: **Shengwu Zhang**, Fujian (CN)

(**) Term: **15 Years**

(21) Appl. No.: **35/518,447**

(22) Filed: **Aug. 5, 2023**

(80) **Hague Agreement Data**

Int. Filing Date: **Aug. 5, 2023**

Int. Reg. No.: **DM/231558**

Int. Reg. Date: **Aug. 5, 2023**

Int. Reg. Pub. Date: **Sep. 22, 2023**

(30) **Foreign Application Priority Data**

Jul. 14, 2023 (CN) 202330441309.4

(51) **LOC (14) Cl.** **23-01**

(52) **U.S. Cl.**

USPC **D23/261**; D23/260

Hibbent sink drain strainer Jun. 14, 2024 found on Jul. 25, 2024 at: <https://www.amazon.co.uk/Hibbent-Strainer-Stainless-Anti-Clogging-Standard/dp/B0CXX5BR1L/?th=1> (Year: 2024).*

Primary Examiner — Jennifer Rivard

Assistant Examiner — Jonathan E Fiencke

(57) **CLAIM**

The ornamental design for sink drainage plug as shown and described.

DESCRIPTION

2. Sink drainage plug

2.1: Top perspective

2.2: Front

2.3: Back

2.4: Left

2.5: Right

2.6: Top

2.7: Bottom

2.8: Bottom perspective

2.9: Top perspective view shown in a state of use

2.10: Exploded top perspective

2.11: Exploded bottom

1 Claim, 11 Drawing Sheets
